CLAIM

The ornamental design for a display screen or portion thereof with graphical user interface for continuous glucose monitoring, as shown and described.

DESCRIPTION

FIG. 1 is a front view of a display screen or portion thereof with graphical user interface for continuous glucose monitoring showing our new design according to a first embodiment; and,

FIG. 2 is a front view of a display screen or portion thereof with graphical user interface for continuous glucose monitoring showing our new design according to a second embodiment.

The outer perimeter illustrated by solid lines in the drawings illustrates a display screen or portion thereof.

The broken lines illustrating portions of the graphical user interface form no part of the claimed design.
